(57) **CLAIM**

We claim the ornamental design for a golf club head, as shown and described.

DESCRIPTION

FIG. 1 is a top right perspective view of a golf club head embodying our new design.

FIG. 2 is a right side elevational view of the golf club head of FIG. 1.

FIG. 3 is a top plan view of the golf club head of FIG. 1.

FIG. 4 is a front elevational view of the golf club head of FIG. 1.

FIG. 5 is a left side elevational view of the golf club head of FIG. 1.

FIG. 6 is a rear elevational view of the golf club head of FIG. 1; and,

FIG. 7 is a bottom plan view of the golf club head of FIG. 1.

The broken lines are included for illustrative purposes only, and form no part of the claimed design.
